UNITED STATES PATENT OFFICE.

PAUL F. GODLEY, OF MONTCLAIR, NEW JERSEY.

DESIGN FOR A FRAME FOR A LOUD-SPEAKER DISK.

Application filed December 31, 1925. Serial No. 15,910. Term of patent 3½ years.

To all whom it may concern:

Be it known that I, PAUL F. GODLEY, a citizen of the United States, residing in the town of Montclair, county of Essex, and State of New Jersey, have invented a new, original, and ornamental Design for a Frame for a Loud-Speaker Disk, of which the following is a specification, reference being had to the accompanying drawing, forming a part thereof, in which—

Figure 1 illustrates a view of the frame, shown in front elevation, and Figure 2 a side elevation thereof.

I claim—

The ornamental design for a frame for a loud-speaker disk, as shown.

PAUL F. GODLEY.
